UNITED STATES PATENT OFFICE.

FRANK M. MICHAEL AND THOMAS V. SCOTT, OF ALLEGHENY,
PENNSYLVANIA.

CURTAIN-POLE.

SPECIFICATION forming part of Letters Patent No. 738,691, dated September 8, 1903.

Application filed January 8, 1903. Serial No. 138,285. (No model.)

To all whom it may concern:

Be it known that we, FRANK M. MICHAEL and THOMAS V. SCOTT, citizens of the United States of America, residing at Allegheny, in the county of Allegheny and State of Pennsylvania, have invented certain new and useful Improvements in Curtain-Poles, of which the following is a specification, reference being had therein to the accompanying drawings.

This invention relates to certain new and useful improvements in curtain-poles; and the primary object of the invention is to provide novel and efficient means for supporting a curtain without the aid of rings and pins, as in the ordinary construction.

A further object of the invention is to construct a pole wherein the curtain may be easily secured either prior to the placing of the pole in position or after said pole has been placed in proper position on the window.

Briefly described, the invention comprises a pole having a bore extending from end to end thereof, said bore being eccentric of the pole and located adjacent to the lower side of the pole and opening along said lower side in a slot through which the curtain to be supported projects. The curtain is wrapped upon the securing rod or member, which is substantially square in cross-section, whereby one corner thereof will protrude into the slot along the lower side of the pole and the opposite side faces of the rod or securing member will impinge the curtain against the walls of the slot, while the remaining three corners of the securing rod or member will be presented to the curtain, whereby to more effectively prevent the slipping of the latter. In connection with the pole we also preferably mount the knobs at the ends of the pole eccentrically of said pole, whereby they may be turned around in order to uncover the ends of the bore and permit the inserting of the curtain and securing rod or member into said bore, all of the above construction to be hereinafter more fully described, and specifically pointed out in the claim.

In describing the invention in detail reference is had to the accompanying drawings, forming a part of this specification, and wherein like numerals of reference indicate

like parts throughout the several views, in which—

Figure 1 is a detail perspective view of a part of a curtain-pole, partly in section, showing the manner in which the curtain is held therein. Fig. 2 is a side elevation of the same with the curtain removed. Fig. 3 is a transverse vertical sectional view. Fig. 4 is an end view showing the knob turned around, whereby to uncover the bore of the pole to permit the insertion or withdrawal of the securing rod or member.

In the present illustration of our invention we have shown a curtain-pole as cylindrical in form, though of course this is not essential to the operation of the device, as a pole of other exterior contour might be employed. We provide the pole 1 with an eccentric bore 2, extending from end to end of the pole and located adjacent to the lower side of the pole and opening at its lower side through the slot 3. In connection with the eccentrically-bored pole 1 we employ a securing rod or member 4, which is substantially square in cross-section and which is made of a length equal to the pole, or at least equal to the width of the curtain which is to be supported. The curtain 5 has its upper end wrapped around this securing rod or member, as seen in Fig. 1 of the drawings, the securing rod or member being positioned so that its one edge or corner will bind the curtain against the side walls of the slot 3, as seen in Fig. 1 of the drawings. The other edges or corners of the securing rod or member will also be presented to the curtain 5. Describing this more fully, it is to be noted that the edge or corner 6 of the securing rod or member protrudes into the slot 3, whereby the side walls of the securing rod or member at opposite sides of the edge or corner 6 impinge against the curtain 5 and bind the same against the side walls of the slot 3, while the edges or corners 7 of the rod or member are presented to the curtain. In practice the curtain is wrapped around the securing rod or member, and the curtain and rod are then inserted into the bore of the pole. In order that the curtain and rod may be inserted into the pole without removing the ornamental end knobs 8, with which curtain-poles are usually provided, we provide

these knobs with a pin 9, which is connected to the knob and is engaged in the eccentrically-placed opening 10 in the end of the pole. When these knobs are turned or swung 5 around, as seen in Fig. 4, the bore of the pole will be sufficiently uncovered to permit the insertion of the curtain and rod or member or the withdrawal thereof, and when the knob is turned down to cover the ends of the bore 10 the rod is retained in position and prevented from longitudinal movement within the pole.

It is to be noted that any weight placed upon the curtain will serve to bind the same more tightly upon the rod, which will effectually prevent the curtain from being pulled 15 out of the pole.

It will be noted that various changes may be made in the details of construction without departing from the general spirit of our 20 invention.

Having fully described our invention, what

we claim as new, and desire to secure by Letters Patent, is—

A curtain-pole provided with an eccentric bore extending from end to end and opening 25 along the lower side of the pole in a slot, in combination with a securing-rod substantially square in cross-section and placed within the pole in such a position that its one edge or corner will project into the slot to bind the 30 curtain between said rod and the walls of the slot, and rotatable knobs eccentrically mounted in the ends of the pole and adapted to normally close the ends of the bore, substantially as described.

In testimony whereof we affix our signatures in the presence of two witnesses.

FRANK M. MICHAEL.
THOMAS V. SCOTT.
